CLUTCH

Harry Morris, Erie, Pa., assignor of one-half to
Alfred Fritzsch, Cleveland, Ohio

Application August 7, 1941, Serial No. 405,817

9 Claims. (Cl. 192—45.1)

This invention relates to a clutch between relatively movable parts and more particularly to the embodiment of a one-way clutch in a wrench.

One of the objects of the present invention is to provide such a clutch which is quick acting and positive in operation when the relatively movable parts between which the clutch is interposed are moved in one direction.

Another object is to provide such a clutch which has a very positive clutching action in one direction and permits free relative movement of the parts in the opposite direction.

Another object is to provide a wrench embodying such a clutch.

Another object is to provide such a wrench which is superior to conventional forms of ratchet wrenches in point of convenience of manipulation. In conventional ratchet wrenches the handle must be swung through a considerable arc before an interlocking of the head and handle of the wrench is effected, thus rendering this type of wrench useless when attempted to be used in a restricted space, whereas a wrench embodying the present invention is immediately positive in operation.

Another object is to provide such a wrench in which the parts are fitted with close tolerances thus providing a minimum of play and lost motion in the operation of the wrench.

Another object is to provide such a wrench which is strong in construction and of which breakage in use is practically impossible and which is not liable to get out of order or require repairs.

Another object is to provide such a clutch which is particularly applicable for use as a one-way clutch.

In the accompanying drawing:

Fig. 1 is a plan view of a wrench embodying the present invention.

Fig. 2 is a vertical, longitudinal section taken on line 2—2, Fig. 1.

Fig. 3 is a fragmentary horizontal section taken on line 3—3, Fig. 2.

Fig. 4 is a fragmentary horizontal section taken on line 4—4, Fig. 2 and showing an exaggerated position of some of the parts illustrated in Fig. 3 and hence to that extent is diagrammatic.

Fig. 5 is an enlarged perspective view of the lock shoe employed in the present invention.

Fig. 6 is an enlarged perspective view of the cam pin employed in the present invention.

The present invention is illustrated in the drawing, as being embodied in a hand operated wrench, although the present invention can be

employed where a one-way locking device or quick acting positive clutch between two relatively movable parts is desired and is equally applicable where the indicated motion of the parts is either rectilinear or rotary.

Referring to the drawing, the wrench is shown as comprising a substantially flat head or housing 10 provided with a cylindrical bore 11 near its front end, a smaller partially cylindrical bore 12 adjacent its rear end and an opening or slot 13 having parallel side walls connecting the bores 11 and 12. A cylindrical receptacle 14 is fitted in the bore 11 and is adapted to rotate in this bore, this receptacle 14 being provided with an out of round opening 15 to receive a nut, bolt head, socket extension rod or the like and being also formed to provide a pair of bosses 16, 16 each of which is formed on one side of the cylindrical receptacle and surrounds the opening 15. It is to be understood that the cylindrical receptacle 14 can be replaced by any suitable form of part to be turned as long as this part is provided with a cylindrical peripheral portion which fits in the bore 11.

25 A lock shoe 18 is arranged in the slot 13 and is rectangular on three sides, the fourth side 19 being concavely arcuate in form and substantially concentric with the axis of the cylindrical receptacle 14. The concave arcuate face 19 is also shown as provided with a pair of spaced vertically extending lugs 20, 20, as best shown in Fig. 5, the outer faces of these lugs 20 also being concentric with the axis of the receptacle 14.

20 While only two lugs 20 have been shown any number can be employed. The opposite sides of the lock shoe 18 are closely fitted to the corresponding side walls of the slot 13 thus permitting the lock shoe to move translationally a slight distance in this slot for a purpose hereinafter more fully described so that the vertical lugs 20 can frictionally engage the periphery of the cylindrical receptacle 14.

30 35 40 A cam member or cam pin, indicated generally at 22, is arranged in the smaller partially cylindrical bore 12 and comprises a partially cylindrical stem or pin portion 23 having a flat face 24 and a pair of rectangular end heads 25, 25, the corresponding forward faces of these end heads being coplanar with the flat vertical face 26, as best shown in Fig. 6. The partially cylindrical stem 23 is closely fitted in the partially cylindrical bore 12 and this bore serves as a bearing for the stem.

45 50 55 To retain the receptacle 14 and lock shoe 18 within the housing 10 a pair of flat plates 26, 26

are removably secured by screws 27 or in any other suitable manner to the opposite flat faces of the housing 10, the bosses 16 projecting through corresponding openings provided in the plates 26.

The handle of the wrench is shown as comprising a pair of spaced outer handle plates 30, 30 and an inner spacer plate 31 disposed between the outer plates 30. The handle plates 30 and 31 can be secured together in any suitable manner but are illustrated as being removably secured together by screws 32. The spacer plate 31 is of shorter length than the outer handle plates 30 and these outer handle plates adjacent their forward ends are each outwardly offset, as best shown in Fig. 2, so as to embrace the rear end of the housing 10. Each of the handle plates 30 is provided with a rectangular opening 33 which receives the corresponding rectangular end head 25 of the cam pin 22.

The housing 10 is urged and maintained in a very slightly offset relation to the handle of the wrench and for this purpose a spring 35 is arranged between the housing 10 and the spacer plate 31, the opposite ends of the spring 35 being received in recesses 36 and 37 provided, respectively, in the housing and the spacer plate. The direction in which the housing 10 is urged and maintained by the spring 35 relative to the handle is represented in Fig. 3 by the arrow 38. Fig. 4 represents an exaggerated position of the parts shown in Fig. 3 with the exception of the spring 35 which is omitted for purposes of clarity. From an observation of Fig. 4 it will be noted that one side of the flat face 24 of the cam pin 23 bears against the rear face of the lock shoe 18 thus urging the lock shoe to a forward position whereby the lugs 20 are urged into frictional engagement with the periphery of the receptacle 14. The resilience of the spring 35 is sufficient to maintain the lock shoe 18 and cam pin 22 in the positions of these parts represented in Fig. 4 in which the handle is slightly offset relative to the housing 10. When pressure is applied to the handle in the direction of the arrow 39, in Fig. 3, and the arrow 40, in Fig. 4, the frictional engagement of the lock shoe with the receptacle 14 is increased and the clutching action between these parts is rendered certain. Thus the handle attempts to rotate the lock pin 22 which by camming action urges the lock shoe 18 into firm engagement with the receptacle 14 which is fitted over the part to be turned. The greater the pressure applied to the handle the firmer will be the frictional engagement of the lock shoe with the receptacle and it has been found that no slippage of the parts occurs.

When it is desired to slip the wrench, the handle is turned in the direction opposite to that indicated by the arrows 39 and 40, the excessive applied pressure being thereby relieved and the pressure of the spring 35 being also slightly relieved so that the handle can be rotated in this opposite direction without effecting a corresponding rotation of the receptacle 14. Thus, the cam pin 22 is rotated very slightly relative to the housing 10 in a clockwise direction as viewed in Figs. 3 and 4 so that the lock shoe 18 is not held in firm frictional engagement with the periphery of the receptacle 14 but is merely held in light frictional engagement solely by the pressure of the spring 35. This light spring pressure can never be counteracted in use by this movement of the handle since the lock shoe slips around the receptacle.

An important feature of the invention resides in the proper proportioning of the sizes of the cylindrical receptacle 14 and the cam member or pin 23 and their respective bores 11 and 12. To obtain proper operation of the wrench I have found it essential that the diameter of the cylindrical receptacle 14 and its bore 11 be at least two and one-half times the diameter of the cam member or pin 23 and its bore 12. With the receptacle 14 having a diameter at least two and one-half times the diameter of the cam member or pin 23, the wrench will operate smoothly and without binding or irregularity in its action.

When it is desired to have the wrench operate in the reverse direction from that illustrated the wrench is turned upside down. To indicate in which direction the handle should be turned to effect a clutching action the handle is provided on each side with an arrow 41.

While I have described the one-way clutch forming the subject matter of the present invention as embodied in a wrench it is readily apparent that the present invention is capable of a variety of applications and embodiments of clutches.

From the foregoing it will be seen that the present invention provides a clutch between relatively movable parts which is quick acting and positive in operation so as to frictionally interlock the parts when the parts attempt to move relatively in one direction and to permit free relative movement in the opposite direction.

I claim as my invention:

1. A clutch interposed between two relatively rotatable parts one of which is provided with an external cylindrical peripheral portion of relatively large diameter, comprising a lock shoe adapted to frictionally engage with said external peripheral portion of one of said parts, and a cam member rotatable about an axis arranged eccentrically of said one part and operatively connected to the other of said parts and adapted to engage the opposite side of said lock shoe from that engaging said external peripheral portion of said one part, said lock shoe being urged into firm frictionally clutched engagement with said one part upon rotation of said other part in a predetermined direction and said lock shoe permitting free relative rotation between said parts upon movement of said other part in an opposite direction.

2. A clutch interposed between two relatively rotatable parts one of which is provided with an external cylindrical peripheral portion of relatively large diameter, comprising a lock shoe adapted to frictionally engage with said external peripheral portion of one of said parts, a cam member of relatively small diameter rotatable about an axis parallel with the axis of said one part and arranged radially outward from said shoe and operatively connected to the other of said parts and adapted to engage the opposite side of said lock shoe from that engaging said external peripheral portion of said one part, and means constantly urging said cam member into engagement with said lock shoe whereby said lock shoe is urged into light frictional contact with said peripheral portion, said lock shoe being urged into firm frictionally clutched engagement with said peripheral portion upon movement of said other part in a direction supplementing the pressure applied by said urging means and said lock shoe permitting free relative movement between said parts upon movement of said other

75

part in a direction in opposition to the pressure applied by said urging means.

3. A clutch interposed between two parts which are relatively rotatable about a common axis and one of which parts is provided with an external cylindrical peripheral portion of relatively large diameter, comprising a housing rotatably mounted on said external peripheral portion of said one part, a lock shoe arranged in said housing and adapted to frictionally engage with said peripheral portion, means for guiding said lock shoe to move radially toward and from the axis of said one part, and a cam member mounted in said housing radially outward from said shoe and rotatable about an axis parallel with the axis of said one part and operatively connected to the other of said parts and adapted to engage the opposite side of said lock shoe from that engaging said external peripheral portion of said one part, said lock shoe being urged into firm frictionally clutched engagement with said one part upon rotation of said other part in a predetermined direction and said lock shoe permitting free relative rotation between said parts upon movement of said other part in an opposite direction.

4. A clutch interposed between two parts which are relatively rotatable about a common axis and one of which parts is provided with a cylindrical peripheral portion, comprising a housing provided with a cylindrical bore which receives said cylindrical peripheral portion of said one part and said housing also being provided with a second bore remote from said first bore and with a parallel walled slot connecting said bores, a lock shoe arranged in said slot for sliding movement therein radially toward and from said first bore and adapted to frictionally engage with said peripheral portion of said one part, a cam member rotatably mounted in said second bore and operatively connected to the other of said parts and adapted to engage said lock shoe, and spring means interposed between said housing and said other part and operating to constantly urge said cam member into engagement with said lock shoe whereby said lock shoe is urged into light frictional contact with said peripheral portion of said one part, said lock shoe being urged into firm frictionally clutched engagement with said peripheral portion upon movement of said other part in a direction supplementing the pressure applied by said spring means and said lock shoe permitting free relative rotative movement between said parts upon movement of said other part in a direction in opposition to the pressure applied by said spring means.

5. A clutch interposed between two parts which are relatively rotatable about a common axis and one of which parts is provided with a cylindrical peripheral portion, comprising a housing provided with a cylindrical bore which receives said cylindrical peripheral portion of said one part and said housing also being provided with a second bore remote from said first bore and with a parallel walled slot connecting said bores, the walls of said slot extending radially of said first bore, a lock shoe arranged in said slot for sliding movement therein radially toward and from said first bore and having its adjacent side adapted to frictionally engage with said peripheral portion of said one part, a cam member rotatably mounted in said second bore and operatively connected to the other of said parts and adapted to engage the side opposite said adjacent side of said lock shoe, and spring means interposed between said housing and said other part and operating

to constantly urge said cam member into engagement with said lock shoe whereby said lock shoe is urged into light frictional contact with said peripheral portion of said one part, said lock shoe being urged into firm frictionally clutched engagement with said peripheral portion upon movement of said other part in a direction supplementing the pressure applied by said spring means and said lock shoe permitting free relative rotative movement between said parts upon movement of said other part in a direction in opposition to the pressure applied by said spring means.

6. A wrench, comprising a housing, a part to be turned mounted in said housing, a lock shoe arranged in said housing and adapted to frictionally engage with said part, a cam member mounted in said housing and adapted to engage said lock shoe, a handle operatively connected to said cam member, and spring means interposed between said housing and said handle and constantly urging said cam member into engagement with said lock shoe whereby said lock shoe is urged into light frictional contact with said part, said lock shoe being urged into firm frictionally clutched engagement with said part upon movement of said handle in a direction supplementing the pressure applied by said spring means and said lock shoe permitting free relative movement between said part and said handle upon movement of said handle in a direction in opposition to the pressure applied by said spring means.

7. A wrench, comprising a part to be turned and having a cylindrical peripheral portion, a housing rotatably mounted on said peripheral portion, a lock shoe arranged in said housing adjacent said peripheral portion of said part and adapted to frictionally engage with said peripheral portion, a cam member rotatably mounted in said housing adjacent said lock shoe and adapted to engage said lock shoe, a handle operatively connected to said cam member, and a spring interposed between said housing and said handle and constantly urging said cam member into engagement with said lock shoe whereby said lock shoe is urged into light frictional contact with said cylindrical peripheral portion of said part, said lock shoe being urged into firm frictionally clutched engagement with said peripheral portion upon the application of pressure to said handle in a direction supplementing the pressure applied by said spring and said lock shoe permitting free relative movement between said part and said handle upon the application of pressure to said handle in a direction in opposition to the pressure applied by said spring.

8. A clutch between two relatively rotatable parts one of which is provided with an external cylindrical peripheral portion of relatively large diameter fitting in a bore provided in the other of said parts comprising a locking member mounted in said other part externally of said one part for radial movement toward and from the peripheral portion thereof and having a concave side embracing a part of said periphery of said one part and cam means rotatable about an axis arranged radially outward from said locking member and engaging with said locking member to force its concave face into locking engagement with said periphery of said one part.

9. A clutch interposed between two parts which are relatively rotatable about a common axis and one of which parts is provided with a cylindrical peripheral portion, comprising a housing provided with a cylindrical bore which receives said cylindrical peripheral portion of said one part and

said housing also being provided with a second bore remote from said first bore and with a parallel walled slot connecting said bores, a lock shoe arranged in said slot for sliding movement therein radially toward and from said first bore and adapted to frictionally engage with said peripheral portion of said one part, and a cam member rotatably mounted in said second bore and hav-

ing a flattened face adapted to engage said locking shoe, the diameter of said first cylindrical bore being at least two and one-half times the diameter of said second bore and said lock shoe being urged by said cam member into firm engagement with said one part upon movement of said other part in a predetermined direction.

HARRY MORRIS,
